Attorney

UNITED STATES PATENT OFFICE.

CHARLES M. VAN VLECK, OF UHRICHSVILLE, OHIO.

BENCH-HOOK.

SPECIFICATION forming part of Letters Patent No. 309,998, dated December 30, 1884.

Application filed October 23, 1884. (No model.)

To all whom it may concern:

Be it known that I, CHARLES M. VAN VLECK, a citizen of the United States, residing at Uhrichsville, in the county of Tuscarawas and State of Ohio, have invented certain new and useful Improvements in Bench-Hooks; and I do hereby declare the following to be a full, clear, and exact description of the invention, such as will enable others skilled in the art to which it appertains to make and use the same.

My invention relates to certain new and useful improvements in bench-hooks, the object of the same being to provide a carpenter's bench with an adjustable bar or hook, the means for adjusting said bar or hook being attached under the bench and to one side of the same, as will be hereinafter more fully set forth.

In the accompanying drawings, which illustrate my invention, Figure 1 is a perspective view. Fig. 2 is a sectional view; and Fig. 3 is a side view.

A represents a carpenter's bench, the upper portion of which is recessed for the reception of a plate, B, which is provided with a rectangular passage-way, C, for the reception of the bench-hook. The side pieces, C', of this passage-way project so as to form bearings for a horizontal shaft, D, which is provided between said side pieces with a gear-wheel, E. The side c of the passage-way C is cut away so as to allow the gear-wheel E to pass through the same and engage with the rack-teeth e, formed on the lower portion of the bench-hook. The upper portion of the bench-hook is provided with serrations, e', with which the board or other object will engage, and the wall c' is provided at its upper portion with a recess, f, upon which the lower serration will rest when the hook is withdrawn entirely within the casing.

G represents a metallic shell, which is provided with a projecting flange, g, which is secured within a recess in the depending side A' of the bench. This plate is provided with a perforation, through which the shaft D passes, and said shaft is provided on the outer side of said plate with a ratchet-wheel, h, and a serrated disk, H, for turning said shaft. Pivoted to the plate G is a pawl, I, having a

thumb-piece, i, for raising said pawl, the pawl being held in engagement with the ratchet-wheel by a spring, j.

The operation of my invention is as follows: 55 To raise the hook the disk H is turned, causing the gear-wheel E to rotate, which engages with the teeth on the bench-hook, and said bench-hook is held in a raised position by the ratchet-wheel, the pawl of which prevents the 60 rotation of the shaft. To lower the bench-hook, the pawl I is raised and the shaft turned in an opposite direction, the flange f abutting against the lower one of the teeth e', thus preventing the hook being depressed below the surface 65 of the bench.

I am aware that prior to my invention bench-hooks have been constructed which are provided with rack-teeth, with which engage a worm-wheel which is connected to a shaft having a handle which operates horizontally, the same being let into a recess in the surface of the bench. This construction is objectionable, owing to the fact that the recess in the upper surface of the bench is liable to become 75 filled with refuse matter, which has to be removed before the handle can be turned.

I claim—

1. In a bench-hook, the casing C, depending from the upper surface of the bench and provided with side flanges, in combination with the shaft D, having a gear-wheel which engages with teeth formed on the bench-hook, said shaft D being provided at its outer end with a ratchet-wheel and milled disk, the former engaging with a spring-pawl, substantially as shown, and for the purpose set forth. 80

2. In combination with the bench-hook having teeth formed on its lower end, a horizontally-supported shaft having a gear-wheel 90 which engages with said teeth, said shaft being provided at its outer end with a ratchet-wheel and milled disk, said ratchet-wheel engaging with a spring-pawl, substantially as shown, and for the purpose set forth. 95

3. In a bench-hook, the plate B, having depending therefrom a casing consisting of sides C' C' c c', a horizontal shaft journaled therein and provided with a gear-wheel, which engages with rack-teeth formed on the bench-hook, the end of said shaft being journaled in a flanged plate, G, and provided with a ratchet-

wheel, *h*, and spring-pawl *I*, with a projecting portion, *i*, substantially as shown, and for the purpose set forth.

4. In a bench-hook, the casing *C*, provided near its upper portion with a recess, *f*, which forms a stop against which the lower one of the teeth *e* abuts, in combination with the shaft *D*, having a gear-wheel which engages with the teeth formed on the bench-hook, said shaft being provided at its outer end with

a ratchet-wheel and disk, said ratchet-wheel engaging with a spring-pawl, substantially as set forth.

In testimony whereof I affix my signature in presence of two witnesses.

CHARLES M. VAN VLECK.
